AIR-CONDITIONING SYSTEM

Earle R. Mandle, Seattle, Wash.

Application November 11, 1933, Serial No. 697,643

5 Claims. (Cl. 62—139)

My invention relates to air conditioning, more especially to the cooling of rooms, houses, auditoriums, theatres, schools, factories, and like interior spaces, though the term "interior space" is used in the general sense of any space, whether enclosed wholly or partly, or not at all, wherein air to be conditioned or cooled is circulated, or into which space air is discharged, this air having been cooled or being cooled by or during such circulation.

The cooling effect of evaporation of moisture is well known. This effect has been employed heretofore to cool the air which is circulated within or discharged into an interior space to be conditioned, but because such air of necessity must be humid, because of the vaporized moisture, the lowering of the temperature of such air did not accomplish the cooling effect intended or expected, for moist air, that is, air where the relative humidity is high, is not so readily bearable as dry air, that is, air where the relative humidity is low, though it be of the same temperature. For any given quantity of moisture in the air, the relative humidity is higher at a lower temperature. Such systems therefore have not been found practicable since, while the air is cooled, the interior space is rendered uncomfortable by reason of the high relative humidity.

Attempts have been made to cool interior spaces by means of mechanical refrigeration. Such systems however, are highly expensive both in installation and in operating cost for moderately cooling a room, auditorium, theatre, or factory.

It is an object of the present invention to devise an air conditioning system, and the several parts thereof, which can operate through the employment of the principle of cooling by evaporation of moisture without the disadvantages formerly inherent in such systems, and which will operate to cool interior spaces to a comfortable temperature at a very low cost, and by a medium, water, which is always available. It is also an object to devise such a system which can be installed and operated at low cost, whereby it may be within reach of every home owner, as well as operators of theatres, auditoriums, factories and like larger spaces.

It is a further object of my invention to devise a system which can be so installed that the cooling of unit spaces can be controlled as desired, so that the system is flexible and easily controllable.

Other objects, and especially such as relate to

mechanical or installation details, will be understood as this specification progresses.

My invention comprises the novel air conditioning system, and the novel parts and arrangement of such parts relative to each other, and the novel method of air conditioning, all as illustrated in the accompanying drawings, described in this specification, and as will be more particularly pointed out in the claims which terminate the same.

Figure 1 is a plan view, with parts broken away, of a typical arrangement of the essential parts of the system, and Figure 2 is a side elevation of the same with parts broken away.

Figure 3 is a side elevation of a modified system, parts being broken away and other parts being shown diagrammatically.

A typical installation is shown in Figures 1 and 2. A heat transfer unit, such as a water-filled radiator 1, is located within what may be termed an exterior conduit 2, to distinguish it from the interior conduit 3, the latter being the conduit by which air is circulated from the room or interior space, and thence back to such a space. Air entering the conduit 2, may, however, be drawn from the interior space, but preferably is drawn from an exterior space, or other space quite separate from the interior space to be cooled. Regardless of its source it is kept separate from the air in the conduit 3 and is discharged to an exterior space, namely, to some space other than that which contains or receives the interior air and which is to be cooled. Thus the inlet 20 to the conduit 2 may extend from outside the house, and the discharge 21 is directed outside the house again, so that the air passing through the conduit 2 is taken in from the outside and discharged again to the outside, passing through the radiator unit 1 between the intake and discharge. As a means to accomplish circulation of the air 1 may provide a fan 23 secured on a shaft 4, the latter driven by any suitable means (not shown).

The interior conduit 3 is provided with one or more inlet connections 30, and preferably with a number of discharge connections 31. To accomplish air circulation in this interior conduit 1 may provide a fan 33, which receives the air from the inlet connections 30, and discharges it through the conduit 3 to the discharge connections 31, and between the inlet and discharge connections is interposed a heat transfer unit 11 which may take the form of a water-filled radiator, whereby heat in the air is absorbed by the water as it passes through this radiator unit 55

11, and the air discharged from the interior conduit 3 is cooler than the air which enters this conduit.

In order to dissipate the heat taken up by the radiator unit 11, this may be formed as a part of the complete heat transfer unit, the other part of which constitutes the radiator 1, and to this end the two radiator parts are connected by a hose connection 12 and by pipe connections 13 10 and 14, extending to and from a pump 10 suitably driven from the shaft 4, as by means of the belt 43 and pulley 44, the latter being illustrated as mounted upon the same shaft as drives the fans 23 and 33.

15 Discharging within the exterior conduit 2, in advance of the radiator unit 1, is a spray nozzle 5, controlled by a valve 50, whereby a fog of water droplets may be discharged within the conduit. Any equivalent means, as for example, 20 discharge of water directly upon the unit 1, may be employed. This moisture is picked up by the air passing through the conduit 2, and the heat in the water in the radiator unit 1 is delivered to this humid air as it passes through the radiator, and causes evaporation of the entrained moisture. The water having given up some of its heat, it is now cooler. Similarly, the air has 25 been cooled, which further cools the water in the radiator unit 1. This water is circulated 30 back to the radiator unit 11, and as the interior air, free from moisture or at least bearing no more than the natural moisture present, passes through this radiator unit 11, it is cooled prior to discharge at 31, and the water in the radiator 35 unit 11, which has picked up heat from the interior air, is circulated back to the radiator unit 1, there to effect further evaporation of water particles suspended in the humid air in the exterior system, and to be again cooled by such 40 evaporation.

It will be evident that the result of such a system is to maintain the interior air free from added humidity, and to employ the humid air only in the exterior system, thereby effecting cooling 45 of the circulating interior air by the effect of evaporation in the exterior conduit. However, if the interior air is so dry that it can stand some added moisture, a further drop in temperature may be obtained by means of a second spray 50 nozzle 51 controlled by a valve 52, and discharging into the interior conduit 3. Not only is the interior air cooled in such case by the relatively cool water in the radiator unit 11, but it is also cooled by the further evaporation of moisture in 55 the interior air.

While I have shown a water-cooled radiator unit in each conduit, and a pump and water connections, it will be evident that the heat transfer unit considered as a whole may be of any 60 suitable type, and that heat might be transferred from the interior conduit 3 to the exterior conduit 2 by any suitable means, for instance, purely or in part by conduction through metal. Furthermore, while water would ordinarily be employed as the circulation medium, on account of its universal availability and cheapness, other media might be substituted therefor as the circulating medium—indeed, other media might be employed for discharge from the nozzle 5.

70 It is indeed not essential that there be an interior conduit as such, and in the system illustrated in Figure 3 there is none. The exterior conduit is the same as before, or may be substantially the same, but instead of delivering 75 water from the primary radiator unit 1 by means

of the pump to a single radiator unit 11, and thence back to the radiator unit 1, the pump 10 delivers water through the conduit 15, whence by branches 16 it is delivered to small individual radiator units 11', which may be located in individual rooms. The water from these individual units is discharged by branch pipes 17 back to a pipe 18, whence it discharges into the radiator unit 1. The various branches are controlled by suitable valves 19, so that any one or more of 10 these units 11' may be supplied with water, cooling only such rooms as may be required.

Behind each of these units 11' is preferably supported a fan 6 driven by an electric motor 60 or the like, whereby air in the room is caused to 15 circulate through the units 11', thus picking up heat from the room to be absorbed in the evaporation of water at the radiator unit 1. The circulation of air in the open room thus becomes 20 the equivalent of its circulation through the closed interior conduit 3 of the system first described.

In some regions water is scarce, and it is within the province of my invention to collect and reuse any excess water discharged into the exterior conduit, and in the interior conduit, if water is 25 discharged thereinto. The means to accomplish this are well known, and any suitable means may be employed. It does not matter that the temperature of this water may become elevated somewhat, since it is the drop in temperature caused 30 by evaporation of water which cools the water in the radiator unit 1, not the absolute temperature of the water discharged into the exterior conduit.

What I claim as my invention is:

1. An air-conditioning system for cooling air in an interior space to a temperature appreciably below the temperature of air in an exterior space, comprising a heat exchange device filled with fluid under substantially constant pressure, and 40 including two units, one over which interior space air passes and one over which exterior space air passes, and means to supply liquid to the exterior space air in advance of its passage over its heat exchange device unit, in quantities not 45 appreciably in excess of that which can be evaporated by heat supplied by the fluid in the exterior space unit, by evaporation of the liquid supplied by said means to cool the fluid in the heat exchange device to a temperature below that of 50 the interior space air, the heat exchange device fluid in turn cooling the interior space air.

2. An air-conditioning system for cooling air in an interior space to a temperature appreciably below the temperature of air in an exterior space, 55 comprising a heat exchange device completely filled with liquid and including two units, one over which interior space air passes and one over which exterior space air passes, means to circulate the liquid at substantially constant pressure from 60 the interior space air unit to the exterior space air unit and back to the interior space air unit, and means to supply atomized water to the exterior space air in advance of its passage over its heat exchange device unit, by evaporation of 65 the water to cool the liquid in the heat exchange device to a temperature below that of the interior space air, such liquid in turn cooling the interior space air.

3. An air-conditioning system for cooling air 70 in an interior space to a temperature appreciably below the temperature of air in an exterior space, which comprises a heat transfer device filled with liquid under substantially uniform pressure throughout, means to conduct interior space air 75

- past a part of said heat transfer device, means to conduct exterior space air past another part of said heat transfer device, means to circulate the contained liquid from one such part of the 5 heat transfer device to the other such part, and means to supply a vaporizable liquid to the exterior of such part past which the exterior space air moves, in quantities not appreciably in excess of that which can be vaporized by the heat 10 of the liquid contained therein, thus by evaporation of such vaporizable liquid to cool such part of the heat transfer device, and by circulation of the cooled liquid therein to cool the interior space part of the heat transfer device.
- 15 4. An air-conditioning system for cooling air in an interior space to a temperature appreciably below the temperature of air in an exterior space, comprising an interior air conduit and an exterior air conduit, a water-filled radiator unit in 20 each conduit, means interconnecting said radiator units for circulation of water therebetween, pump means for circulating the water, and means to spray water into said exterior conduit in advance of the radiator unit therein to be carried by the exterior air, hotter than the interior air, over such radiator unit, and by evaporation of the atomized water to cool the water in the radiator 5 unit to a temperature below that of the interior air, which in turn cools the interior air.
5. An air-conditioning system for cooling air in an interior space to a temperature appreciably below the temperature of air in an exterior space, 10 comprising a fluid-filled, constant pressure heat transfer device, means to pass relatively warm exterior space air over a part thereof, means to spray a vaporizable liquid into such air in advance of the heat transfer device to be carried 15 thereagainst in atomized form, thereby by evaporation of the atomized liquid to cool the whole, and means to pass interior space air, cooler than the exterior space air, over the remainder of said heat transfer unit, to be further cooled thereby. 20
